UNITED STATES PATENT OFFICE.

SIDWELL M. ENGLISH AND LAGRANGE V. EDMONDSON, OF RENOVO, PENNSYLVANIA.

LIQUID-FUEL BURNER.

1,083,604.

Specification of Letters Patent.

Patented Jan. 6, 1914.

Application filed February 25, 1913. Serial No. 750,474.

To all whom it may concern:

Be it known that we, SIDWELL M. ENGLISH and LAGRANGE V. EDMONDSON, citizens of the United States, residing at Renovo, in the county of Clinton and State of Pennsylvania, have invented certain new and useful Improvements in Liquid-Fuel Burners, of which the following is a specification.

Our invention relates to improvements in liquid fuel burners, the object of the invention being to provide an improved construction which insures the even distribution of liquid fuel throughout an extended surface, and compels the liquid fuel to move over the end of an inclined platform in a thin layer, extended throughout the width of the platform or in a plurality of relatively small streams and commingle with air forced under the lower end of said platform, and thoroughly intermix with the air to form a good burning mixture.

A further object is to provide in a burner of the character stated, a liquid fuel distributing platform which is inclined from one end to the other, and on its upper face is formed with a plurality of longitudinal grooves which communicate at their upper ends with a relatively large transverse passage having at the center thereof, a conical distributor whereby the liquid fuel is caused to uniformly enter the several grooves and discharge uniformly at the lower ends of said grooves, so that the fuel is equally distributed throughout the entire width of the platform and insures a proper commingling of the fuel and the air, so that a rich uniform mixture is had, the proportion being controlled by the feed of liquid fuel.

With these and other objects in view, the invention consists in certain novel features of construction and combinations and arrangements of parts as will be more fully hereinafter described and pointed out in the claims.

In the accompanying drawings: Figure 1 is a view in side elevation illustrating our improvements. Fig. 2 is a view in longitudinal vertical section. Fig. 3 is a view in section on the line 3—3 of Fig. 2. Fig. 4 is a view in section on the line 4—4 of Fig. 2, and Fig. 5 is a fragmentary view in transverse section on an enlarged scale on the line 5—5 of Fig. 3.

Our improved burner comprises a single integral casting consisting of an outer casing 1 of general rectangular form which at its

inlet end merges into an air chamber 2 in the form of an elbow. A relatively large pipe 3 communicates with the lower end of the elbow, and is adapted to be connected to any suitable fan blast apparatus. A relatively small pipe 4 communicates with an opening 5 in the rear end of the elbow in line with the center of casing 1. This pipe 4 is adapted to be connected to any suitable compressor or source of supply for compressed air, so that air may be forced through the casing. It is, of course, to be understood that these different sources of air are to be used separately and not together in accordance with the facilities at hand.

In the casing 1, our improved inclined liquid fuel distributing platform 6 is located. This platform 6 is integral with the casing, extends from side to side thereof, merges into the top of the casing at the upper end of the platform, and at its lower end terminates above the bottom of the casing and short of the discharge end of the casing as clearly shown in Fig. 2. This platform 6, on its upper face, is provided with a series of parallel grooves 7, the series extending throughout the entire width of the platform and adapted to convey the liquid fuel to the lower end of the platform over which it falls and commingles with the air passing under the lower end of the platform and burns at the point of juncture.

Near the upper end of platform 6 and on its upper face, an integral distributor 8 is provided, and this distributor is of general conical form, although it is not a true cone, yet all of its sides taper to a point at the top of the distributor, and this pointed end is in line with the center of a liquid fuel inlet 9 in the top of casing 1, and to which fuel is fed by a pipe 10 connected to any suitable source of supply.

The upper face of platform 6 at its upper end is formed with a transverse passage 11 into which the rear half of the distributor 8 extends, and at its ends said groove curves slightly downward, and discharges directly into the outer groove 7. By reference particularly to Fig. 5, it will be seen that all of the grooves, with the exception of the two central grooves, communicate with this passage 11, but at the entrance ends of said grooves 7, their bottoms are in a slightly higher plane than the bottom of passage 11. This difference in elevation is graduated, so

that the grooves nearest the center have their bottoms higher than the others from the intermediate portions toward the sides of the platform. This is designedly true 5 because the central grooves receive the upper surface of the liquid fuel, and each groove in turn receives a lower level of fuel, so that by the time the fuel passes to the outer groove 7, each groove will have received 10 its proper quota of liquid fuel, and such liquid fuel will be flowing down the several grooves at an even depth, so that it is equally distributed throughout the entire surface of the platform.

15 As above stated, the distributor 8 is not a true cone, but is somewhat flattened on its upper side, so that the liquid fuel will pass in greater proportion into the passage 11, than into the central grooves 7, so that by 20 this means a better distribution of the liquid fuel is had. This equal distribution is carried out even with the smallest quantity which can be fed, because the pointed conical distributor compels the liquid to divide 25 and run down the sides thereof into the several grooves, when it falls from the inlet 9.

Various slight changes might be made in the general form and arrangement of parts 30 described without departing from our invention, and hence we do not limit ourselves to the precise details set forth, but consider ourselves at liberty to make such changes and alterations as fairly fall within the 35 spirit and scope of the appended claims.

Having thus described our invention, what we claim as new and desire to secure by Letters Patent is:

1. A liquid fuel burner comprising a casing 40 having a fuel inlet in its top, an inclined liquid fuel distributing platform in the casing, said platform having a series of longitudinal grooves in its upper face, and a tapering distributor in line with the fuel inlet to 45 said casing, said distributor located at the upper end of the platform, and adapted to compel the liquid fuel to divide and pass uniformly down the several grooves of the platform, substantially as described.

50 2. A liquid fuel burner comprising a casing having a fuel inlet in its top, an inclined liquid fuel distributing platform in the casing, terminating at its lower end above the bottom of the casing, means for directing air

through said casing and under the lower 55 end of said platform, said platform having a series of longitudinal liquid fuel carrying grooves on its outer face, an inclined distributor having a pointed upper end in line with the inlet in the top of the casing whereby the liquid fuel falling upon the distributor will be compelled to pass uniformly 60 down the grooves in the platform, substantially as described.

3. In a liquid fuel burner, the combination 65 with a casing having a fuel inlet in its top, of an inclined oil distributing platform in the casing, said platform having on its upper face a series of longitudinal grooves, and at its upper end a transverse passage, 70 said passage at its ends communicating with the end grooves of the platform, and between its ends communicating with the ends of the intermediate grooves, the latter located at different elevations with relation 75 to the bottom of the passage in regular ratio from the outer to the inner grooves, and an inclined distributor located centrally with relation to the passage and the grooves and in line with the fuel inlet in the top of said 80 casing, substantially as described.

4. A liquid fuel burner consisting of an integral casting comprising a rectangular horizontal portion having an integral elbow at one end, an air blast pipe communicating with the 85 lower end of said elbow, a compressed air supply pipe communicating with the rear wall of the elbow, an inclined integral platform in the casing extending from side to side thereof, and at its upper end merging 90 into the top wall of the casing, said platform at its lower end terminating short of the end of the casing and above the bottom of the casing and having a series of longitudinal grooves on its upper face, said casing 95 having a liquid fuel inlet in its top adjacent the upper end of the platform, and a conical distributor integral with the platform and located in line with said fuel inlet, substantially as described.

100 In testimony whereof we have signed our names to this specification in the presence of two subscribing witnesses.
